UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

APPARATUS FOR MAKING STENCILS.

1,177,935.

Specification of Letters Patent.

Patented Apr. 4, 1916.

Original application filed September 26, 1914, Serial No. 863,654. Divided and this application filed February 25, 1915. Serial No. 10,389.

To all whom it may concern:

Be it known that I, ALBERT B. DICK, a citizen of the United States, residing at Lake Forest, in the county of Lake and State of Illinois, have invented certain new and useful Improvements in Apparatus for Making Stencils, of which the following is a specification.

My invention relates to the art of making stencils and particularly to the art of preparing a stencil for use upon a duplicating machine in making multiple copies.

By my invention, stencils may be made expeditiously and accurately from an electro-type, block of type, or other form of printed matter, or other matter having sharply defined surfaces from which it is desired a stencil should be cut to be subsequently used in making duplicate copies.

20 The object of my invention is to provide a novel apparatus for preparing stencils.

In my application Serial No. 863,654, filed September 26, 1914 is described and claimed a novel method of making stencils in the 25 manner referred to.

My present application is a division of my application Serial No. 863,654 referred to, and will describe and claim suitable apparatus by which the method referred to may 30 be carried out.

My improved method as described in my earlier application referred to, consists, primarily and broadly, in pressing the stencil lightly against the stencil-making member a 35 plurality of times, as by placing the stencil in position upon the electro-type or other stencil-making member and forming the stencil from this member by the cumulative effect of a considerable number of applications of pressure upon the stencil-sheet, the 40 impacts of the pressing body being light and insufficient individually to form a stencil of the desired sharpness and depth.

More specifically, the method preferably 45 comprises laying the stencil-sheet upon the stencil-making member, securing the stencil-sheet at one extremity and then applying pressure lightly as described a plurality of times in such a manner as to constantly hold 50 the stencil-sheet under tension, the pull of the sheet upon its securing devices being, however, insufficient to cause the sheet to creep or move relatively to the stencil-cutting member.

I have found that when a stencil-sheet is 55 laid upon an electro-type or other member from which it is desired to form a stencil from which, for example, a page of printed matter is to be duplicated, and the stencil-sheet is held at one end and a roller passed 60 over the sheet with a sufficient amount of pressure to cause the stencil to be cut at a single operation, the pressure required is sufficient to injure the roller and also the electro-type or type surface used for cutting 65 the stencil as well as for the backing of the type matter. Such an operation also results in the formation of a poor stencil. If a stencil is attempted to be made by passing a 70 roller or rollers over the stencil-sheet a number of times with comparatively heavy pressure, a blurred effect will be caused because of the creep of the paper, due to the considerable tension exerted lengthwise upon the same, so that such a stencil is unfit for 75 commercial use. I have found, however, that the roller may be passed over the stencil-sheet with a light pressure a number of times, for example, from nine to twelve 80 times, with the result that a perfect clearly defined stencil is produced, the pressure exerted being insufficient to cause creep of the paper and insufficient to injure the type surface or the roller, the stencil being cut by the cumulative effect of the repeated applications of the pressure. The machine or apparatus which will be described and claimed herein constitutes an effective and rapid 85 means for practising the method briefly described above. In this apparatus, a plurality of pressure rollers are carried by endless carriers to pass continuously in operation over the surface of the stencil-sheet, the rollers passing over the sheet from the direction of the end of the sheet at which the latter is secured to its support and one or another of the rollers preferably constantly 90 being in contact with the stencil-sheet. Means are provided for regulating the pressure exerted by the rollers upon the sheet 100 and type matter under the same, this regulating means preferably consisting in mechanism for raising or lowering the support on which the type matter and stencil are carried toward or away from the plane in which the rollers move above the stencil-sheet. Preferably the electro-type or other stencil-cutting member and the stencil-sheet there- 105

on are mounted so that the lines of type in the stencil-cutting member are disposed at a slight incline to the axes of the impression rollers, which results in a more uniform and 5 clearly defined stencil than if the lines of type were parallel to the axes of the pressure rollers.

A particular field of usefulness of the machine briefly described lies in the making of 10 stencils to be used for duplicating printed forms. According to my invention a stencil of a standard printed form having spaces therein to be subsequently filled in by individual data may be prepared by the method 15 above briefly described for an electrotype or other printing member. The stencil is then removed from the printing member and the spaces left in the printed form filled in on the stencil as by inserting the stencil-sheet 20 in a typewriting machine where the remainder of the characters to be printed are cut in the stencil by operation of the typewriting machine in the usual manner, care being observed to secure exact registrations of these 25 characters with the matter previously cut in the stencil from the electrotype. The stencil may then be applied to the drum of a stencil-duplicating machine for use in printing multiple copies from the stencil in the usual manner. By this process, work may be done by stencil duplication which previously was chiefly carried out by other 30 methods. In many classes of work it has been common to use printed forms for various 35 purposes and to fill in the blanks of these forms with a typewriter which is often an exceedingly laborious method. It has not been practicable to fill in the blanks of these forms with a stencil-duplicator for the 40 reason that proper registration of the new matter with the matter of the printed form has not been commercially attainable. By my method, a stencil of the completed form with the spaces filled in may be obtained in 45 an efficient, economical and clear cut manner, as stated, by making the stencil of the electrotype or printed form in the manner described and then filling in the spaces on a typewriter, whereby a stencil is obtained 50 from which as many copies as desired may be printed of the completed form.

In order that my invention may be more fully understood, attention is hereby directed to the accompanying drawings, forming 55 part of this application and illustrating a preferred form of mechanism for making a stencil from an electrotype or printing member.

In the drawings, Figure 1 represents a 60 longitudinal section of the preferred machine, Fig. 2 is a side elevation of the same, certain parts being omitted, Fig. 3 is a plan view of the machine, broken away and sectioned in part, Fig. 4 is a transverse section 65 taken on line 4-4 of Fig. 1, Fig. 5 is an

enlarged transverse section of the bar by which the stencil-sheet is secured in position, Fig. 6 is an enlarged partial plan view of one end of the stencil-sheet secured in position above the printing member, Fig. 7 70 is a partial section of the same, taken on line 7-7 of Fig. 6, Fig. 8 is a plan view of a stencil-sheet which has been formed by the machine described and Fig. 9 represents the same sheet in which various blanks of the 75 same have been filled in by cutting the appropriate characters on the stencil-sheet on a typewriter.

Referring to the drawings, the machine is represented as having a base 1 from 80 which rise side-frames 2 and 3. The shafts 4 and 5 mounted in the side frames carry cams 6 and 7 on which the support 8 is mounted. The shaft 4 is provided with a crank-handle 9, and shafts 4 and 5 are provided with cranks 10 and 11, connected by a rod 12, so that rotation of the handle 9 results in an equal rotation of the cams 6 and 7 and a consequent raising or lowering of the table 8. Crank handle 9 may be 90 held in any adjusted position by the coaction of a pair of spring-pressed pins thereon with the holes 13 in a sector 14 secured to the side-frame 2, these pins having rounded ends, and being adapted to enter the holes a 95 slight distance only, so that by applying a little force to the handle it may readily be moved onward.

The electrotype or other printing member 100 is mounted upon the table 8 and may be secured thereto in any desired manner as by screwing the same to the face of the table. Preferably a sheet of somewhat yielding rubber 16 is interposed between the printing member and the table. The stencil-sheet 17 105 with its backing sheet 18 is placed upon the face of the printing member and secured as will be described. Preferably, a bar 19 is made use of for securing one end of the stencil backing-sheet adjacent to one end of the 110 printing member, this bar resting upon the table 8 with its vertical face 20 contacting the forward face of the electrotype, if an electrotype be used as the printing member, or contacting the forward face of the chase if 115 the printing member comprises a form of type set up in a chase. The bar 19 may be screwed to the table or it may be secured to the printing member which is secured to the table. In this case, a projection or lip 21 120 upon the forward edge of the electrotype or chase of type extends over the curved forward edge 22 of bar 19 and is secured to the bar by screws 23, passing through the lug 21 and into webs 24 in the bar. Bar 19 is 125 provided with an upper rear surface 25 which slopes downwardly to the rear and on which is mounted the button-bar or device 26 for securing the end of the backing-sheet. Bar 19 is provided with a number of up- 130

wardly extending screw-threaded pins 27 over which the openings or button-holes 28 at the end of the stencil backing-sheet are slipped, after which bar 26 is positioned 5 upon the end of the composite stencil and the nuts 29 carried by bar 26 are screwed tight upon pins 27 to tightly hold the end of the backing-sheet, to which is suitably secured the stencil-sheet. Bar 26 is provided 10 with flanged members 30 which coat with flanges 31 on nuts 29 to prevent the nuts being separated from the bar and lost. Surface 25 on which bar 26 is located is given the downward inclination referred to so that 15 the devices for securing the backing-sheet and therefore the stencil-sheet will be substantially below the plane in which the face of the printing member 15 is located to prevent the heads of the thumb-nuts 29 being 20 struck by the impression members in their movement.

The impression rollers are carried, as stated, by a flexible carrier or carriers, one flight of which will carry the rollers into co- 25 action with the stencil-sheet. As illustrated, the machine is provided with shafts 32 and 33 extending between the side-frames on which are mounted sprocket wheels 34 and 35 over which pass sprocket chains 36 and 30 37 one inside of each side-frame of the machine. The impression rollers 38 are carried by the chains 36 and 37 in parallel relation, the rollers being rotatably mounted on shafts 39 carried by links of the chain. 35 The rollers are preferably three in number, although my invention is not limited in this respect, and are preferably formed of hard rubber and are spaced at equal distances apart on the chains. The side-frames 2 and 40 3 are provided with horizontal guides 40 extending inwardly and the shafts 39 on which the rollers are mounted are provided adjacent their ends with disks 41 which contact the under sides of guides 40 as the rollers 45 travel in their upper flight above the stencil-sheet, so that movement of the rollers in a horizontal plane above the stencil-sheet and printing member is assured. The pressure which is exerted between the rollers 38 and 50 55 the stencil-sheet and printing member on which the same is carried is regulated by raising the table 8 by means of hand-crank 9 until the desired light impact of the rollers upon the stencil-sheet is secured. The machine may be operated in any desired manner, such as the hand-crank 42, which is connected by gears 43 and 44 to the sprocket shaft 33.

In operation, the stencil-sheet is positioned 60 as described above the printing member, the pressure between the rollers and the stencil being adjusted so that the desired light impact of the rollers with the stencil is secured, the pressure being insufficient to injure the rollers or the type and insufficient 65

to cause lengthwise moving or creeping of the stencil-sheet relative to the printing member as the rollers pass over the stencil-sheet, the stencil being formed by the cumulative effect of the repeated light applications of pressure. As the rollers pass over the sheet, they contact the latter first adjacent the edge at which it is secured to the backing-sheet adjacent to the buttonholes in the latter, and as preferably there is always 70 one roller in contact with the sheet, the latter exerts a constant slight pull upon its securing devices.

Preferably, the printing member 15 with the stencil-sheet thereon is disposed at a 80 slight angle to the vertical axis of the machine, or, to put it differently, so that the lines of type on the printing member are disposed at a slight angle to the axes of the impression rollers. By this means, less pressure need be exerted upon the pressure rollers than if the latter contacted the whole of the first and each subsequent line of type at the same instant, and accordingly, sharper definitions of the characters cut on the stencil are obtained when the printing member is mounted in the angular manner described and the tendency to injure the stencil, at points corresponding with the type lines, is minimized.

It is obvious that my invention may be carried out with different details of construction from those described, so long as a plurality of pressure-exerting members are caused to pass over the stencil-sheet in the 90 manner described.

A stencil-sheet having form data cut therein by an electrotype or other printing member is illustrated in Fig. 8. In Fig. 9 the same stencil is shown with further characters, such as those illustrated at 45, formed thereon by other means, such as the operation of a typewriting machine as stated, this figure illustrating the completed stencil which is adapted for use in a stencil-duplicating machine.

Having now particularly described my invention, what I claim and desire to protect by Letters Patent is as follows:—

1. In apparatus for making stencils, the combination of a support, a stencil-making member thereon, means comprising a button-bar for securing a composite stencil-sheet on said member, said composite sheet containing a backing-sheet having button-holes adjacent the end thereof, pressure rollers, means for causing the rollers to pass in succession over the stencil-sheet, to successively press said sheet against said member, and means for adjusting the pressure 115 exerted by said rollers on the stencil-sheet, substantially as set forth.

2. In apparatus for making stencils, the combination of a support, a stencil-making member thereon, means for securing one end 120

4

of a composite stencil-sheet to said support, so that the sheet will lie upon said member, said composite sheet containing a backing-sheet having button-holes adjacent the end 5 thereof to be engaged with said securing means, a plurality of pressure devices, a pair of endless flexible carriers by which the devices are carried, means for moving the carriers to cause the devices to successively 10 pass over the stencil-sheet, from the direction of the end of the sheet at which the latter is secured, and means for adjusting the pressure exerted by the devices on the sheet and stencil-making member thereunder, substantially as set forth.

3. In apparatus for making stencils, the combination of a support, a stencil-making member thereon, means for securing one end of a composite stencil-sheet to said member, so that the sheet will lie upon said member, said composite sheet containing a backing-sheet having button-holes adjacent the end thereof to be engaged with said securing means, a pair of flexible endless carriers mounted to be movable over said sheet from the direction of the end of the sheet at which the latter is secured, a plurality of parallel pressure devices carried by said carriers, and means for causing said devices to 20 contact the sheet, in their passage over the same, with a relatively light pressure, said devices being so spaced upon the carriers that one of the same is always in contact with the sheet in the operation of the device, substantially as set forth.

4. In apparatus for making stencils, the

combination of a support, a stencil-making member thereon, means for attaching a composite stencil-sheet to said member, comprising a bar adapted to be secured to said member having attaching devices for the stencil-sheet situated below the plane of the face of said member, a flexible carrier mounted to be movable over said sheet from the direction of the end of the sheet at 40 which the latter is secured, a plurality of pressure devices carried by said carrier, adapted to successively press the sheet against said stencil-making member, means for causing said devices to move in a plane 45 parallel to the face of said member, and means for adjusting the pressure between said devices and said member and sheet thereon, substantially as set forth.

5. In apparatus for making stencils, the combination of a support, a stencil-making member thereon, and means for attaching a composite stencil-sheet in position to overlie said member, comprising a bar adapted to abut against one end of said member and 50 having a downwardly and rearwardly inclined upper surface, and attaching devices for a stencil sheet mounted on said surface with the upper ends of the same below the plane of the face of said member, substantially as set forth.

This specification signed and witnessed this 23rd day of February, 1915.

ALBERT B. DICK.
